Allen Ingalls

United States Patent Office.

ALLEN INGALLS, OF HARTWICK TOWNSHIP, NEW YORK.

Letters Patent No. 77,045, dated April 21, 1868.

IMPROVEMENT IN SLEIGH-BRAKE.

The Schedule referred to in these Letters Patent and making part of the same.

Be it known that I, ALLEN INGALLS, of the town of Hartwick, in the county of Otsego, and State of New York, have invented a new and useful Sleigh-Brake, for holding back sleighs as they go down hill; and I do hereby declare that the following is a full, clear, and exact description thereof, reference being had to the accompanying drawings, and to the letters of reference marked thereon.

The nature of my invention consists in the construction of a suitable apparatus or piece of mechanism, made of iron or steel, or both combined, to attach to any kind of a sleigh, to be operated by the driver without moving from his seat, by which he can hold back the sleigh, and thereby ease the horses.

A is the sleigh, which may be built either on the bob or long-sleigh plan. B are the brake-irons or spurs, which may be constructed of any suitable shape to hold on to the ice or snow, as they pass over it. These spurs are placed, one on each side of the sleigh, and connected together by rod C, said rod C being attached to the rive or frame of the sleigh. D is a lever, attached to either the box or frame of the sleigh. E is the foot-lever, attached to the sleigh, by which the brake is operated. F is a rod, which connects the levers D and E. G is a rod, which connects the brake-iron and lever D.

To use my invention, the driver presses the foot-lever forward, which forces the end of the spur against the ground, and thereby holds back the sleigh, and when not needed, pulls back the lever E, which raises the spur from the ground, and allows the sleigh to move as freely as if it had no brake attached.

What I claim as my invention, and desire to secure by Letters Patent, is—

The brake-irons B, combined with levers D and E, rods F and G, and sleigh A, arranged as described and set forth, for the purpose specified.

ALLEN INGALLS. [L. S.]
